[57] CLAIM

The ornamental design for the power converter casing, as shown and described.

DESCRIPTION

FIG. 1 is a perspective view of the power converter casing;

FIG. 2 is a side elevational view taken from the right side thereof of the power converter casing;

FIG. 3 is a front elevational view which is identical to the rear elevational view of the power converter casing;

FIG. 4 is a side elevational view taken from the left side thereof of the power converter casing;

FIG. 5 is a top plan view of the power converter casing; and,

FIG. 6 is a bottom plan view of the power converter casing.

FIG. 3

FIG. 4

FIG. 6

FIG. 5
